UNITED STATES PATENT OFFICE.

NATHANIEL J. PRITCHARD, OF ROANOKE, VIRGINIA, ASSIGNOR TO THE PRITCHARD BRAKE COMPANY, OF SAME PLACE.

AIR-BRAKE.

SPECIFICATION forming part of Letters Patent No. 410,922, dated September 10, 1889.

Application filed October 20, 1888. Serial No. 288,618. (No model.)

To all whom it may concern:

Be it known that I, NATHANIEL J. PRITCHARD, a citizen of the United States, residing at Roanoke, in the county of Roanoke and State of Virginia, have invented certain new and useful Improvements in Air-Brakes; and I do hereby declare the following to be a full, clear, and exact description of the invention, such as will enable others skilled in the art to which it appertains to make and use the same.

My invention relates to an improvement in devices for applying and relieving the pressure on railway-brakes, the object thereof in part being to simplify and make more efficient the device whereby the admission of air to the brake-cylinder is regulated and controlled, and also to so regulate the exhaust that the engineer may better adjust and hold any desired degree of pressure upon the brakes; and the invention consists, essentially, in the construction, arrangement, and combination of parts, substantially as will be hereinafter described and claimed.

In the accompanying drawings, illustrating my invention, Figure 1 is a vertical section of my improved device for applying pressure to pneumatic railway-brakes, together with the engineer's valve, the train supply-pipe, and the train exhaust-pipe, the several parts being shown in the position that they assume when the brakes are released. Fig. 2 is a vertical section similar to that of Fig. 1, the parts being in the position that they occupy when the brakes are set. Fig. 3 is a horizontal partial section on the line $x-x$ of Fig. 1. Fig. 4 is a horizontal partial section on the line $y-y$ of Fig. 1. Fig. 5 is a detail section of the engineer's valve and certain of the adjacent parts, showing the arrangement of the same when straight air is to be applied to the brakes.

Like letters of reference designate corresponding parts throughout the several figures.

The casing within which the essential parts of my improved device for applying pneumatic pressure to railway-brakes are arranged is preferably of a general cylindrical form having any suitable dimensions and made in any desired manner, it being adapted for arrange-

ment beneath the car or other structure with which it is used. It may be made in one or more parts, as preferred. I have represented in the drawings a convenient way of making it, it being shown as consisting of the main cylindrical body A' , upon the top of which is secured the convex head A , while the lower part is closed by the convex end piece A^2 . Within this casing are located two horizontal diaphragms or partitions of gum, gutta-percha, rubber, or other elastic substance or material, the edges of the upper of said diaphragms B being secured between the convex head A and the main cylindrical body A' , while the edges of the lower of said diaphragms B' are secured between the end piece A^2 and the main body. These elastic diaphragms, being of elastic material, will (under the pressure of the air) be expanded or contracted, so as to take either the position shown in Fig. 1 or that shown in Fig. 2; or, if the air-pressure above and below the same should exactly balance, the diaphragms might at certain times be accurately horizontal.

The casing is provided with ports at points where the several pipes are coupled thereto, which are used with the ordinary air-brake and lead to the essential parts of the same. Thus a denotes the port near the upper end of the casing above the upper diaphragm B , where a coupling is made with the pipe that leads to the auxiliary reservoir or air-drum. b is the port in the wall of the main cylindrical body A' between the two diaphragms, where the pipe is connected leading to the brake-cylinder. c is a port located near the lower end of the case below the diaphragm B' , where a connection is made with the main train-pipe C , that supplies air from the air-reservoir to the device. d is the exhaust-port in the internal horizontal tubular extension A^3 of the main cylindrical portion A' of the casing, and at the point where said port is located the train exhaust-pipe is coupled to the casing, which exhaust-pipe runs from said casing to the engineer's valve, and into it the air is exhausted.

Centrally within the space between the two diaphragms is located a light metallic casting or frame having an eccentric vertical stem E ,

recessed to contain a valve, as will be herein-after explained. This vertical stem is integral at its upper end with a flat plate E', that rests in contact with the under surface of the 5 diaphragm B, and has a sleeve or bushing E², projecting upward through a central opening in said diaphragm. A washer G encircles the sleeve E² and rests close upon the top of the diaphragm B, and an open slotted or cage-like cap or head F is firmly screwed upon the sleeve E² down upon the washer. In this 10 way the central casting is securely fastened to the upper diaphragm. The lower end of the eccentric stem E is integral with the flat portion E', which rests in close contact with the upper surface of the diaphragm B', and has a central projection E³, that extends downward through the diaphragm, receiving upon its lower end a washer e and a nut f, so that 15 the part E', the washer, and the nut are all firmly compacted together. Thus it will be seen that the two diaphragms support the central casting, and that during their expansion or contraction under the air-pressure and 20 their consequent movements up or down said central casting will likewise be elevated or depressed.

Connection between the chamber below the lower diaphragm and the chamber above the 25 upper diaphragm is had through a vertical passage running along the eccentric stem E, and also passing through the upper diaphragm and superimposed washer and the lower diaphragm and washer beneath, said passage being for a certain portion of its 30 length within the stem E, increased in diameter at h to permit the location therein of a valve which may be adjusted to permit the flow of air through the said passage or to 35 obstruct said flow. Evidently various kinds of valves may be devised for use in this connection. I have in the drawings shown one preferable style, which consists of a rod i, extending through the enlarged recess, the 40 passage above the same, and projecting a certain distance outside of the upper diaphragm. Within the enlarged recess h this rod is enveloped by coiled spring j, the rod which is thus enveloped being severed into two parts, 45 which are separated a short distance, as shown, and said spring being tensioned between collars k on the lower portion of the rod and k' on the upper portion of the rod. Beneath the 50 collar k is a ball l, forming a ball-valve, which has its seat upon the end of the air passage-way beneath the enlarged recess h. The upper collar k' has also a seat upon the end of the air passage-way above the enlarged recess. 55

60 The operation of the valve is as follows: In Fig. 1 the valve is shown as open, the ball l being removed from its seat and the collar k' being removed from its seat. This condition of the valve results from the pressure of the air beneath the diaphragm B', which pressure in pushing up the lower diaphragm has also elevated the central casting, likewise the upper 65 diaphragm, and thus the projecting end of the rod i has been brought into contact with an enlargement a' on the convex head, 70 thus causing the collar k' to be sufficiently removed from its seat to permit the passage of air from the recess h upward through the passage above. The force of the air-pressure upon the ball l will remove this ball from its seat, and hence the air beneath the lower diaphragm will have easy course upward through the air-passage and into the chamber above the upper diaphragm. When the pressure beneath the lower diaphragm is exhausted, 75 so as to collapse that diaphragm, then the rod i will drop along with the other parts, and the spring j will operate to close both the collar k' and the ball l upon their respective seats. 80 Within the cage-like or open head F, which 85 is secured to the projecting sleeve E², is a valve G, having its seat upon the end of said sleeve, a tight joint being effected by means of a packing m let into the end of the sleeve upon which the valve-plate rests. This valve 90 G has connected to its upper side the valve-rod G', enveloped by a spring G², which is tensioned between the upper end of the cap F and the valve proper, and acts to close the valve upon its seat. The valve G is also provided with downwardly-projecting radial wings G³, preferably four in number, which 95 extend downward through the sleeve E², and when the valve is in its normal closed position are of sufficient length to extend slightly 100 below the flat plate E'.

The tubular extension A³, which, we have seen, projects horizontally inward from the wall of the middle part A' of the casing, is provided with a valve H, located in the central line of the casing and vertically movable directly beneath the wings of the valve G. The valve H has a seat upon the packing-ring n, let into the upper side of the tubular extension A³. Said valve H has on its upper 105 side four radial wings H', and on its lower side four other radial wings projecting downwardly through the vertical passage in the extension A³, the lower end of said wings carrying a rod H³, which passes through a suitable stuffing-box in the wall of the extension A³, and is adapted to be brought into contact with the lower flat plate E' of the central casting. In Fig. 1, when the air-pressure is beneath the lower diaphragm, the flat plate E', 110 by pressing upon the rod H³ during its upward movement, has resulted in removing the valve H from its seat, thus permitting the exhaust to be opened, so that air coming from the brake-cylinder can pass out through the 115 port d. In Fig. 2, where the air-pressure has been exhausted from beneath the lower diaphragm, the downward movement of the upper flat plate E' has by pressing upon the upper ends of the wings H' closed the valve H, thus 120 closing the exhaust, and the contact of the wings G³ with the upper ends of wings H' has resulted in opening the valve G, so that the air from the auxiliary reservoir easily passes 125 130

through the outlet thus afforded by valve G and on into the brake-cylinder to set the brakes.

I denotes the engineer's valve, which in all the drawings I have preferably shown in section. Its construction is simple, being nothing more nor less than a four-way cock, one of whose openings *o* leads to the air-reservoir; another *p* is the outlet for the exhaust; another *q* is where the train exhaust-pipe is coupled to the engineer's valve, and the last *r* is where coupling is made with the train supply-pipe. When the rotative part I' within the casing I of this engineer's valve occupies the position shown in full lines in Fig. 1, it will be evident at a glance that the air from the air-reservoir can readily pass into the train-pipe, and also that the exhaust from the brake-cylinder which has come through the train exhaust-pipe will enter the valve and pass up through the exhaust-opening *p*. When the part I' has been rotated to occupy the position shown in dotted lines in Fig. 1, it will be obvious that the exhaust will have no outlet through the engineer's valve, since the opening *q* will be closed. Air may still pass, however, from the air-reservoir into the train-pipe. When the valve assumes the position shown in Fig. 2, the current of air from the reservoir to the train-pipe is obstructed and cut off, and air is being exhausted from the main train-pipe.

It is usual in triple valves or other devices having a similar function to that of my present invention to exhaust the air from the brake-cylinder through an outlet-port leading directly to the atmosphere. Instead of doing this, I now propose to provide what is termed a "train exhaust-pipe" D, which is to be coupled to the triple valve or similar device and to extend therefrom to the engineer's valve. The exhaust air, therefore, instead of rushing into the atmosphere, will pass along this train exhaust-pipe to the engineer's valve and have an outlet at that point. It will thus be noted that the engineer will in this way have the exhaustion of the air completely under his control. If he fixes a certain pressure upon the brakes, he can retain and hold that pressure as he may desire. For instance, suppose there is a certain pressure applied to the brakes and that the engineer desires to reduce that pressure without completely removing the brakes. This he can readily do when he has control of the exhaust by simply closing the exhaust, which is effected by a simple manipulation of the engineer's valve into the position shown in dotted lines in Fig. 1. Thus the brakes can be held set to any desired degree of pressure. In Fig. 1, although the exhaust is closed, as shown in dotted lines, yet air is still passing along the main train-pipe, recharging the auxiliary reservoir, and there is no reduction of pressure in it. It is thought that this combination of a triple valve or similar device, a train exhaust-pipe leading to the engineer's valve, and said

valve with the train supply-pipe, is novel in pneumatic brake machinery, and considerable stress is here laid upon this feature, as it is thought to be an advance in the art and a great improvement.

It remains to describe the operation of my improved device for applying pneumatic pressure to railway-brakes. The description of the construction of the parts may be sufficient to set forth with clearness the operation of the device; but it is thought best to supplement this with further description of the operation.

In Fig. 1 we have the normal condition of the parts of the device when the brakes are not applied. Air is passing from the air-reservoir through the engineer's valve into the train-pipe to my improved regulating device, and the pressure beneath the lower diaphragm is such as to expand the same and force it upward. Thus it is obvious that the pressure beneath the lower diaphragm is greater than the pressure above the upper diaphragm. Air is passing from beneath the lower diaphragm through the vertical passage in the stem E, the valve therein being open, as shown, into the chamber above the upper diaphragm, and thence to the auxiliary reservoir. The valve G being closed, air cannot go from the auxiliary reservoir to the brake-cylinder. Any pressure in the brake-cylinder is now exhausting through the device into the train-exhaust and out by way of the engineer's valve, for the exhaust-valve H is open. Suppose now that it is desired to set the brakes. The engineer will manipulate his valve to the position shown in Fig. 2, so that the air-pressure in the train-pipe and beneath the lower diaphragm may be reduced below what it is above the upper diaphragm. This reduction in the pressure will cause the collapse of the two diaphragms, and consequently the closure of the valve within the stem E and the exhaust-valve H and the opening of the outlet-valve G, so that air from the auxiliary reservoir may pass down through sleeve E² beneath the valve G and into the brake-cylinder and set the brakes.

We have already seen that when the engineer has released the brakes and desires to fix them at some diminished pressure, or, in fact, to hold them at any desired pressure, he has the privilege of instantly cutting off the exhaust, and thus retaining the pressure upon the brakes.

In Fig. 5 I have shown the position of the engineer's valve when it is desired to apply straight air to the brakes. In this case the exhaust-valve will be open, as it is in Fig. 1, and the air passing immediately through the train-exhaust from the air-reservoir will go into the brake-cylinder.

Having thus described my invention, what I claim as new, and desire to secure by Letters Patent, is—

1. In a pneumatic brake system, the herein-described device for applying and relieving

the pressure on the brakes, consisting, essentially, in the combination, with an inclosing-case, of two flexible diaphragms arranged transversely within the case to divide it into three chambers, the ports in said chambers leading to the auxiliary reservoir, brake-cylinder, main supply-pipe, and the exhaust-port, an air-passage between the upper and lower chambers, a valve in said passage, an exhaust-valve in the middle chamber, and an outlet-valve between the upper and middle chambers, all substantially as described.

2. In a pneumatic brake system, a device for applying and relieving the pressure on the brakes, consisting in the combination of an inclosing-case, two flexible diaphragms arranged therein, so as to divide said casing into three chambers, the ports in said chambers leading to the auxiliary reservoir, the brake-cylinder, the main supply or train pipe, and the exhaust-port, a valve for controlling the air communication between the end chambers of the casing, the valve for controlling communication between the upper and middle chambers, and the exhaust-valve in the middle chamber, all arranged in the manner and for the purpose set forth.

3. The herein-described device for applying and relieving the pressure on railway-brakes, consisting in the combination of an inclosing-case, two flexible diaphragms arranged within the same to divide it into three chambers, the upper of said chambers having a port leading into the auxiliary reservoir, the middle chamber having a port leading into the brake-cylinder and an exhaust-port, and the lower chamber having a port where the main supply-pipe enters, the air-passage between the upper and lower chambers containing a valve, the exhaust-valve in the middle chamber, and the outlet-valve between the upper and middle chambers, all arranged substantially as described.

4. In a device for applying and relieving the air-pressure on pneumatic railway-brakes, the combination of an inclosing-case, two flexible elastic diaphragms arranged therein to make a triple chamber, suitable ports in the inclosing-case leading to the auxiliary reservoir, the main pipe, the brake-cylinder, and the exhaust, a valve for permitting the passage of air between the upper and lower chambers, an exhaust-valve in the middle chamber for controlling the exhaust, and an outlet-valve between the upper and middle chambers for permitting the flow of air from the auxiliary reservoir to the brake-cylinder, all substantially as described.

5. In a device for applying and relieving the air-pressure on pneumatic railway-brakes, the combination of the engineer's valve, the main air-supply pipe, and the device for applying and relieving the pneumatic pressure on the brakes, consisting, essentially, of an inclosing-casing, two flexible diaphragms arranged within the same to divide it into three

chambers, the upper of said chambers having a port leading into the auxiliary reservoir, the middle chamber having a port leading into the brake-cylinder and an exhaust-port, and the lower chamber having a port where the main supply-pipe enters, the air-passage between the upper and lower chambers containing a valve, the exhaust-valve in the middle chamber, and the outlet-valve between the upper and middle chambers, all substantially as described.

6. In a device for applying and relieving the pressure to air-brakes, the combination of an inclosing-case made in three parts, two flexible diaphragms secured between the junctions of these parts to divide the casing into three chambers, the upper of said chambers having a port leading into the auxiliary reservoir, the middle chamber having a port leading into the brake-cylinder and an exhaust-port, and the lower chamber having a port where the main supply-pipe enters, a central casting attached to and supported by the flexible diaphragms, a valve arranged in said casting for controlling the communication between the two end chambers, a valve likewise arranged in connection with the casting for controlling communication between the upper and middle chambers, and an exhaust-valve in the middle chamber, all substantially as described.

7. The combination of the inclosing-case having suitable ports leading to the auxiliary reservoir, brake-cylinder, main supply-pipe and exhaust, the two flexible diaphragms secured within said case, a central casting attached to and supported by said diaphragms, and having an air-passage which affords a connection between the chamber below the lower diaphragm and that above the upper diaphragm, a valve within said passage, an outlet-valve carried by the upper end of said casting to afford communication between the air-drum and the brake-cylinder, and an exhaust-valve, all arranged substantially as described.

8. The combination of the inclosing-case, consisting of the main cylindrical portion A' and the end portions A and A², flexible elastic diaphragms B and B', secured within the casing, the central casting attached to and supported by said diaphragms, the air-passage through said casting, the exhaust-valve II, and the outlet-valve G, all arranged substantially as described.

9. The combination, with the inclosing-case having suitably-arranged ports and the diaphragms within said case, of the central casting attached to and supported by said diaphragms, and consisting of the eccentric vertical stem E, having the air-passage through it containing a valve, the upper flat portions E', having a sleeve E², and the lower flat portion E', connected to the lower diaphragm, the valve G, arranged in connection with the sleeve E², and the exhaust-valve H,

arranged in connection with the tubular extension A³ on the casing, substantially as described.

10. The combination of the inclosing-case, the two flexible diaphragms, the central casting attached to and supported by said diaphragms, the slotted valve-cover F, secured to the upper end of said casting, the valve G, having a stem G', enveloped by a spring G², and also having downwardly-projecting wings G³, and the exhaust-valve H, arranged in connection with the tubular extension A³ of the casing, and having upper wings H' and lower wings H², carrying a stem H³, all substantially 15 as described.

11. The combination of the casing, the two diaphragms B and B', secured within it, the air-passage running through said casting between the chamber below the lower diaphragm and that above the upper diaphragm, the valve within said passage consisting of a rod i, whose upper end is adapted to come into contact with an enlargement a' on the casing, collars k and k' on the two parts of 20 said rod, which is divided near its lower end, and enveloping spring j between said collars, and a ball l, all substantially as described.

12. The combination of the inclosing-case, two diaphragms B and B', arranged within it, 25 the central casting consisting of the eccentric vertical stem E, having flat portions E' and E', that are secured to said diaphragms, and having an air-passage that affords connection

between the two ends of the casing, a valve within said air-passage having a projecting 35 rod i, adapted to come into contact with an enlargement a' on the casing, an outlet-valve G on the upper end of the central casting, and an exhaust-valve H, for controlling the exhaust-port, substantially as described. 40

13. The combination of the inclosing-casing, two diaphragms B and B', arranged within it, suitable ports leading to the main parts of the brake system, an exhaust-valve controlling the exhaust-port, and a central casting supported and carried by the two diaphragms, and having a valve that controls the flow of air from the auxiliary reservoir to the brake-cylinder, substantially as described. 45

14. The combination of the diaphragms and 50 the casing having an internal projecting extension A³ at the point where the exhaust-port is located, suitably-arranged ports, a valve for regulating the flow of air from the lower end to the upper end of the casing, and 55 the valve for regulating the flow of air from the air-drum to the brake-cylinder, and an exhaust-valve H, having upper wings H' and lower wings H², terminating in a stem H³, substantially as described. 60

In testimony whereof I affix my signature in presence of two witnesses.
